UNITED STATES PATENT OFFICE.

WALTER P. MURPHY, OF CHICAGO, ILLINOIS.

METAL CAR-ROOF.

1,139,363.

Specification of Letters Patent. Patented May 11, 1915.

Application filed May 6, 1914. Serial No. 836,598.

To all whom it may concern:

Be it known that I, WALTER P. MURPHY, a citizen of the United States, and a resident of the city of Chicago, in the county of 5 Cook and State of Illinois, have invented a new and useful Improvement in Metal Car-Roofs, of which the following is a specification.

This invention relates to metal roofs for 10 railway freight cars and the like, and consists in a new type of roof made of plates of heavy gage sheet metal which is free from the defects of heavy gage metal roofs of the types heretofore used.

15 Roofs made of heavy plates riveted together and to the car frame work loose in service and leak. The so-called "flexible" metal car roofs, in which the roof sheets are loosely held upon the roof substructure 20 and are free to move somewhat with respect to each other, are not water-tight and the roof sheets work out of place in service.

The metal car roof which is the principal object of this invention is composed of roof 25 sheets which are rigidly attached to the roof substructure at the ridge, and which are freely movable with respect to the roof substructure at the eaves. The roof sheets are arranged crosswise of the car extending from 30 eaves to eaves, and are lapped and secured together along their adjacent edges, forming a complete water-tight covering for the car irrespective of the roof substructure and of the means for attaching the roof sheets 35 thereto.

40 Other objects and advantages of the invention appear in connection with the following description of the embodiment thereof illustrated in the accompanying drawings.

In the drawings, wherein like parts are designated by the same reference characters in the several views, Figure 1 is a plan view 45 of an end portion of a car roof embodying the invention, top parts of the roof being broken away to disclose the parts beneath; Fig. 2 is a half end elevation of the roof and a half transverse section of the same on the line 2-2 in Fig. 1; Fig. 3 is a side elevation 50 of the portion of the roof shown in Fig. 1; Fig. 4 is a side elevation to a larger scale of a portion of the car at the eaves, showing an eaves cap; Fig. 5 is a cross-section through 55 a portion of the car at the eaves on the line 5-5 in Fig. 1; Fig. 6 is a cross-section

through a portion of the car at the ridge crosswise of a carline, on the line 6-6 of Fig. 1; Fig. 7 is a similar cross-section at the eaves of the car on the line 7-7 in Fig. 1; Fig. 8 is a cross-section of a portion of the 60 car at the eaves lengthwise of the carline, on the line 8-8 in Fig. 1, the carline, bolts and retaining clip being shown in elevation; Fig. 9 is a longitudinal section of portions of the roof at the end of the car on the line 65 9-9 in Fig. 1; Fig. 10 is a side view of the inside of an eaves cap; Fig. 11 is a perspective view of a ridge bolt retaining block; and Fig. 12 is a cross-section through the 70 eaves of a car having a metal frame, showing a modified form of eaves cap in elevation.

In the drawings, the invention is shown applied to a car having wood side plates 11 and end plates 12, but it is also adapted to 75 a car having metal side and end plates.

The roof substructure consists of inverted T-shaped carlines 13 which are bolted to the side plates, and metal purlins 14 of channel shape with their ends supported on and securely riveted to the bottom flanges of the carlines. The ends of the carlines are located in notches in the tops of the side plates, and their extremities are bent down outside 80 of the side plates.

85 Roof sheets 15, which are made of heavy gage sheet metal, are arranged crosswise of the car with their ends resting on the side plates and their middle portion supported on the purlins. The roof sheets are formed with stiffening corrugations 16 which extend from end to end of the sheets at spaced intervals and strengthen them against buckling under any weight likely to come upon them. The roof sheets are somewhat wider 90 than the spaces between the carlines, and their side margins are formed with doubled-up flanges 17 of approximately inverted V-shape having round tops and slanting side walls. These flanges 17 extend from end to end of the roof sheets, and straddle over the vertical webs of the carlines, the proximate flanges of adjacent roof sheetslapping and embracing each other to form standing 95 seams or lap joints between the roof sheets. 100

105 The ends of the roof sheets between the side flanges 17 are provided with straight downturned flanges 18 which overhang the side plates of the car. The end flanges 18 are spaced away from the side plates near 110

the corners of the roof sheets, but they approach the side plates more closely midway of the ends of the roof sheets.

Angle flashing strips 19 are arranged over the outer and upper edges of the side plates from end to end of the car. The lower edges of these flashing strips are offset outwardly and overlap the top ends of the side sheathing boards 20 of the car. The upper edges of the flashing strips 19 are positioned beneath the ends of the roof sheets, and support the latter where the side plates are notched to receive the ends of the carlines.

At each end of the car an angle shield strip 21 is secured to the end plate. The horizontal flange of the angle shield lays over the end margin of the end roof sheet, and its inner edge 22 is bent down to rest flat on the roof sheet within the outer corrugation 16 of the latter.

Seam cover strips 23 of inverted gutter shape are arranged over the standing seams 17 of the roof sheets, with their margins 24 resting on the roof sheets between the seam flanges 17 and corrugations 16. The seam covers are spaced from the tops and side walls of the seam flanges.

The roof sheets are rigidly bolted to the carlines by bolts 25 at the ridge of the car. The heads of the ridge bolts 25 are slipped into dove-tail or inverted T-shaped slots in the top flanges of the vertical webs of the carlines, and are secured therein by perforated saddle blocks 26 which are slipped onto the shanks of the bolts and seated astride of the top webs of the carlines. The tops of the ridge bolt retaining blocks are rounded to conform to the under side of the standing seam flanges of the roof sheets, and the roof sheets rest directly on them. Holes are made in the tops of the seam flanges at the ridge through which the bolts 25 pass.

Saddle shaped washers 27 are seated on the seam flanges at the ridge line, and have their tops shaped to conform to the under side of the seam covers 23. The seam covers have flanged holes at the ridge for the bolts 25.

Nuts 28 are screwed down hard on the tops of the seam covers and firmly secure the latter and the roof sheets to the carlines at the ridge. Leather or soft metal washers 29 may be placed between the nuts 28 and seam covers 23, into which the flanges surrounding the bolt holes in the latter may sink, thereby making tight joints around the ridge bolts to keep out water.

Running board saddles 30 rest upon the seam covers, and are provided with holes at the ridge for the bolts 25 which secure the roof sheets and seam covers to the carlines. The upper ends of the bolts 25 project through the running board saddles, and nuts 31 secure the latter to the roof. The

holes through the running board saddles are counter-bored at their upper and lower ends to form recesses for the nuts 28 and 31. Cover plates 32 are arranged across the running board saddles over the upper recesses. Running boards 33 are nailed to the running board saddles. The end running board saddles rest loosely on the angle shield strips at the ends of the car, and the ends of the running boards project beyond the ends of the car and are secured together and supported by brackets 34.

The seam covers are secured to the car at the eaves by eaves caps 35 which fit over the ends of the seam covers and are bolted to the side plates and to the end of the carlines. The eaves caps are somewhat wider than the seam covers, and their side and front walls cover the open ends of the standing seams and the spaces between the down-turned end flanges of the roof sheets. On their under sides the eaves caps have ledges 36 and webs 37 which rest in the angle of the flashing strips over the side sheathing of the car and thereby position the eaves caps away from the ends of the standing seams. Sufficient space is left between the eaves caps and flashing strips for air to circulate into and out of the car through the ends of the standing seams and between them and the flashing strips. The webs 37 act as vanes or air deflectors, and cause the air current between the eaves caps and flashing due to the motion of the car to blow into the ends of the standing seams on the windward side, and also protect the egress of air from the ends of the seams on the leeward side. The space between the eaves caps and flashing strips also permits the end flanges of the roof sheets to move freely with respect to the eaves of the car. Bolts 38 through the lower ends of the eaves caps secure them and the eaves flashing strips to the side of the car. Bolts 39 with their heads secured in dove-tail or T-shaped slots in the ends of the webs of the carlines project outwardly through the eaves caps and secure the latter to the ends of the carlines. The bolts 39 are held in place in the carline slots by means of V-shaped clips 40 arranged astride of the carline webs and having holes in their two branches which embrace the heads of the bolts.

In Fig. 12 a modified form of eaves cap 41 is shown which is adapted for cars having metal angle or Z-bar side plates 42. The front wall of the eaves cap 41 is spaced from the eaves flashing strips 43 to permit circulation of air into and out of the car. The eaves caps prevent water from blowing directly into the open ends of the standing seams, and at the same time they assist in causing air to circulate into and out of the car and thereby keep the under sides of the roof sheets dry.

From the preceding description it is evident that the roof sheets are mutually dependent, that is, they coöperate to retain each other in position; and collectively they 5 form a substantially complete and self-contained water-tight covering extending from side to side of the car over its full length. The roof sheets are unsecured to the car except along the ridge line; hence lateral vibration and relative lengthwise movement 10 of the sides and ends of the car are not directly transmitted to the roof, and relative movement of one roof sheet with respect to another is not occasioned thereby. The 15 shape of the lapped margins of the roof sheets permits one roof sheet to slip over or under its neighbor lengthwise of the car at the eaves to the limited extent permitted by the eaves fastenings and the seam cov- 20 ers at all times hold the lapped margins of the roof sheets in contact with each other for their entire length; hence the roof can accommodate itself to sagging or bowing of the side plates, or twisting of the sides or 25 ends of the car out of square without the roof sheets becoming spread. Also no movement of the roof plates with respect to each other or with respect to the roof substructure is possible at the ridge, and hence each 30 roof plate is firmly secured in transverse alignment with the center line of the car roof irrespective of the vibration and distortion of the roof substructure.

It is evident that modification may be 35 made in the forms and arrangement of the parts shown in the drawings without departing from the invention, and the invention is not restricted to the specific forms and arrangement shown and described.

40 What I claim as my invention is:

1. A car frame having carlines and longitudinal members connecting the same, load sustaining roofing sheets extending from eaves to eaves covering the entire space there- 45 between and having their side marginal edges overlapped and looped over the carlines, and fixedly attached to the car at the ridge and loosely secured at the eaves to permit movement of the sheets as a whole 50 lengthwise of the car at the eaves independ- ently of the carlines.

2. A car frame comprising side plates, a skeleton roof frame supported by said car frame, and overlapping roofing-sheets sup- 55 ported by said roof frame and covering the car from eaves to eaves, said sheets being fixedly secured to the roof frame at the ridge thereof and loosely supported by said roof frame away from the ridge, and seam 60 caps secured to the substructure in the neighborhood of the eaves and overlapping the joints between said overlapping sheets, said caps being adapted to permit a limited movement of the roof sheets relative to said 65 subsfructure, whereby said car roof perma-

nently maintains its relation to the substructure at the ridge fastenings but is movable relative to the substructure at all other points.

3. A car roof comprising carlines and 70 metal roofing sheets arranged crosswise of the car and supported on said carlines, said sheets having interlocking margins looped over the carlines and fixedly secured to said carlines at the ridge, said sheets being movable relative to the substructure at all other 75 points, and eaves caps over the eaves ends of said looped margins, said caps restraining the movement of said sheets at the eaves.

4. A car roof comprising carlines and 80 metal roofing sheets supported thereby and interlocked at their margins to constitute a complete roof covering, said sheets being fixedly secured together and to the carlines at the ridge and loosely secured to the eaves 85 ends of the carlines, whereby said sheets are movable as a unitary structure along with the middles of said carlines and independently of their ends.

5. A car roof including carlines, and load 90 sustaining roofing sheets attached to the car at the ridge and secured at the eaves in such a way as to permit movement of the sheets as a whole lengthwise of the car at the eaves, the side marginal edges of said sheets over- 95 lapping each other and looped over the carlines by which they are supported.

6. A car roof comprising a series of load 100 sustaining roofing sheets which are loosely overlapped and are rigidly secured together 100 at the ridge to form a continuous covering for the entire car, said covering being movable as a unit relatively to the car at points remote from the ridge, and said roof sheets having a limited amount of movement at the 105 eaves independently of each other.

7. A car roof including a series of rigid load sustaining roofing sheets having over- 110 lapping inverted V shape side marginal edges extending from side to side of the car 110 and secured together at their middle points, said roof spanning spaces between the sides of the car and being movable as a flexible unit relative to the car sides.

8. In a car roof a supporting frame mem- 115 ber, load sustaining roofing sheets extending from eaves to eaves, a running board saddle, nut seats formed in the upper and lower faces of said saddle and a bolt open- 120 ing extending from one seat to the other, a bolt passing through said supporting frame member and through said bolt opening in the saddle and through the roofing sheets, a nut on said bolt in the seat in the under side of the saddle locking the roof sheet to the 125 supporting frame member and a nut in the seat in the upper face of the saddle locking the saddle to said bolt and on the roofing sheets and a cap on the saddle covering the 130 said bolt and nut seats against the elements. 130

9. A car roof comprising a skeleton frame, load sustaining metallic roofing sheets spanning the open spaces of said frame, the side marginal edge portions of adjacent sheets 5 having upstanding interlocking members rigidly secured together at the ridge and constituting a joint between the adjacent sheets flexible transversely thereof at all other points.
10. In a car, a skeleton roof substructure, roof sheets constituting a complete watertight covering supported on said substructure, said roof sheets extending from eaves to eaves and overlapping along their side 15 margins, means for rigidly securing said roof sheets to the roof substructure at the ridge, and means for retaining the side margins of the roof sheets in contact with each other while permitting slight relative movement of the roof sheets with respect to each 20 other at the eaves independently of the distortion of the substructure.
11. In a car, a skeleton roof substructure, roof sheets constituting a complete watertight covering supported on said substructure, said roof sheets extending from eaves to eaves and overlapping along their side 25 margins, means for rigidly securing said roof sheets to the roof substructure at the ridge, and cover strips for retaining the side margins of the roof sheets in contact with each other while permitting slight relative movement of the roof sheets with 30 respect to each other at the eaves independently of the distortion of the substructure, said cover strips being secured to the substructure at the eaves.
12. In a car roof, roof sheets having side
- flanges of inverted V-shape, the proximate flanges of adjacent sheets being superposed 40 to form standing seams with slanting walls, and cover strips of inverted gutter shape straddling said standing seams and spaced therefrom, the lateral margins of said cover strips resting on said roof sheets and retaining them in contact. 45
13. A metal car roof comprising roof plates supported on a skeleton frame and extending from eaves to eaves, means for joining said roof plates together along their 50 side margins, and means at the ridge for retaining said roof plates in central alignment, said roof plates having a limited amount of play on each side of the ridge relatively to said frame. 55
14. A metal car roof comprising roof plates secured together along their side margins and supported on a skeleton frame, means for securing said roof to said frame at the ridge, said roof being free on each 60 side of said ridge to move relatively to said frame.
15. A car roof construction comprising carlines having upstanding webs, roof plates having their side margins secured together, 65 said roof plates being spaced out of contact with said carlines, means for securing said roof plates to said carlines at the ridge, and means for loosely securing the eaves ends of said roof plates. 70

Signed at Chicago, Illinois, this 30th day of April 1914.
